UNITED STATES PATENT OFFICE.

DAVID L. MURCHEY, OF DETROIT, MICHIGAN.

GAME-COUNTER.

1,271,927.

Specification of Letters Patent.

Patented July 9, 1918.

Application filed February 9, 1914. Serial No. 817,483.

To all whom it may concern:

Be it known that I, DAVID L. MURCHEY, a citizen of the United States, residing at Detroit, in the county of Wayne and State 5 of Michigan, have invented certain new and useful Improvements in Game-Counters, of which the following is a specification.

This invention relates to registers or counters for games, and it has for one of its objects the provision of a device which is especially adapted for keeping the tally or score of golf games, the device comprising means whereby the number of strokes or "putts" employed in making any one "hole" 15 may be indicated or registered, the indicated score remaining undisturbed during the playing of a game and until reset by the operator.

The invention has, furthermore, for its object the provision of a device of this character comprising a "total" register which indicates the total number of "putts" used by the player in completing his game.

The invention has also for its object the provision of an improved device of this character comprising means whereby all the several hole indicators or registers may be returned to zero by means which pertain individually to the several registering devices 30 and which are normally held against retraction during their non-operative period.

The invention has, furthermore, for its object the provision of a device which comprises a progressively advancing index ring 35 which is adapted to be engaged by any one of the series of registering devices pertaining to the several holes individually, so as to advance the latter step by step in the same manner as said ring is advanced.

40 Further objects of the invention will hereinafter appear and be particularly defined in the claims.

The invention has been clearly illustrated in the accompanying drawings, in which 45 similar characters denote similar parts and in which:—

Figure 1 is a face view of a golf registering device or counter embodying my invention.

50 Fig. 2 illustrates the same device with the top cover removed.

Fig. 3 is a horizontal section substantially on line indicated 3—3 of Fig. 4.

Fig. 4 is a vertical section of the counter 55 on line 4—4 indicated on Fig. 3.

Fig. 5 is a top view of the member where-

by the several locking devices for the individual "hole" registers are brought into and out of active positions simultaneously.

Fig. 6 is a top view of the base plate, 60 *per se.*

Fig. 7 is a perspective view of one of the slides which carry the "putt" registering devices pertaining to each hole individually.

Fig. 8 is a perspective view of one of the 65 locking members which are employed in connection with the "putt" registering wheels, and

Fig. 9 is a perspective view of a key used for resetting the several registering devices 70 to zero.

Referring to the drawings, 10 denotes a base plate provided with a spaced ring 11 having an internal flange 12 which latter serves to retain for rotatable movement an 75 annulus 13 which constitutes the main operative member of the device and is provided at its outer face with ratchet teeth 14 adapted to be engaged by a pawl 15 (see Fig. 3). A spring 16 serves to hold the pawl 15 in engagement with the ratchet teeth, said pawl being pivoted at 17 to a finger lever 18 which is fulcrumed on one of the screws 19 by means of which the ring 11 and base plate 10, as well as a cover plate 20, are held together. Loosely mounted upon the screw 19 is a dog 21 whereby retrograde movement of the annulus 13 will be prevented. A spring 22 serves to hold the finger lever 18 and dog 21 normally in position shown in Fig. 3. 90

After each stroke or "putt" which a player makes, the finger lever 18 is forced toward the stationary finger piece 23 which constitutes a part of the ring 11, and the annulus 13 is consequently advanced for the distance 95 of one tooth.

In the present instance the device is so organized that the individual number of "putts" or strokes required by a player to make any one of nine holes will be individually registered on a special index wheel pertaining to that particular hole, this registering mechanism comprising in each instance a radially movable slide 24, the main body of which rests upon the base plate 10, while 105 at its inner end it is provided with a downwardly projecting lug 25 adapted to travel in a slot 26 provided in the base plate for that purpose, and a spring 27 normally pushes each slide toward the center of the 110 device.

Each slide 26 serves as a carrier for an

index wheel w , nine of these being provided, that is to say: one for each "hole-register." By referring to Fig. 4 it will be noted that the slide 24 has at its outer end a stud 28 on 5 which is journaled a pinion 29 which has the index wheel w rigidly attached thereto.

Means are provided whereby the slides 24 are radially moved relatively to the center of the device so as to bring the teeth of the 10 pinion into or out of engagement with gear teeth 30 formed on the inner face of the annulus 13, and on the left side of Fig. 4 three teeth are in engagement, while at the 15 right side of Fig. 4 the slide is in its innermost position and the teeth of the pinion are clear from the internal teeth of the annulus. The means for shifting the slides radially, as described, consist preferably of a cam 31 20 journaled on a stud 32 which is rigidly held in the base plate, and the cam groove of which (see Fig. 3) is so constructed that only one of said slides can be in its outward or tooth-engaging position, while all of the 25 other slides are drawn inwardly and are free from such tooth engagement.

The present device is adapted to register the number of strokes required for nine holes, individually and collectively, and the face plate or cover 20 of the instrument has 30 nine number plates n to correspond with the number of holes to be played.

The present indication registered by the instrument shows that the player has not yet passed his play from the third hole for 35 which he has already used seven "putts" or strokes, and in order to clearly indicate this fact, I provide a pointer 33 which is rigid on a finger button 34 which is adapted to be rotated by hand to turn the cam 31 40 into the selected position, the finger button being connected with the hub of the cam by a set screw 35, the inner end of which enters a groove 36 formed on the stud 32 so that in this manner they are all held against separation.

Means are provided whereby each pinion 29 will be maintained in locked or non-rotative position whenever its carrier slide is mounted to bring the pinion out of tooth 50 engagement with the annulus 13, these means consisting in each instance of a pawl 37 which is pivoted at 38 on the base plate and has a tooth 39 normally in the proper position to enter the space between a pair of 55 pinion teeth when the latter is moving in the direction to bring its teeth clear of the teeth of the annulus 13. In other words, the lock pawl 37 is in such position that an engagement will be effected between it and 60 the pinion teeth before the latter have entirely cleared the teeth of the annulus so that consequently no rotation of the pinion can possibly occur, although a coil spring 40 normally tends to rotate the pinion in a 65 retrograde direction so as to bring its indi-

cating disk w into the zero position, as is for instance illustrated in Fig. 2 in which an abutment 41 is provided for each disk, the latter being provided with a lug 42 which will normally rest against the abutment just mentioned.

By referring to Fig. 3 it will be noted that if the cam 31 should be moved for only one-half of the regular one-ninth rotation, from the position shown, all the slides will 75 be in their inward positions and the pinions carried thereby will consequently be free from tooth engagement with the teeth of the annulus, but they will be locked by virtue of the engagement with their respective pawls 80 37. It being understood that the slides have arrived at the limit of their inward movements, as controlled by said cam, I have provided means for withdrawing the several dogs 37 or, more particularly, the teeth 39 85 85 thereof from all of the pinions simultaneously so as to enable the several springs 40 to exercise their functions in returning their several pinions and the indicating devices or wheels carried thereby, back to their normal or zero positions. For this reason I 90 employ a cam plate 41 having a series of cam slots 42, each of which engages an upward projection 43 formed on each pawl (see Fig. 8), said cam plate 41 being mounted for free 95 and independent rotation on the cam hub 31, above described. In order to rotate this releasing cam plate 41 I preferably provide in the body portion thereof a pair of apertures 42 which are adapted to receive a pair of pins 43 (see Fig. 9) of a wrench or key 44, so that in this manner the cam plate 41 may 100 be properly rotated until a pointer 45 carried by said cam plate (see Fig. 5) is brought into register with an index mark r 105 on the face of the dial in which position of the cam, all the pawls are withdrawn from their respective pinions.

In other words: in order to reset the pinions to zero, the slide-cam must first be 110 rotated into an intermediate position, as for instance in register with the index marker r , above referred to, to bring the several pinion teeth clear of the teeth of the annulus, and the cam plate 41 must be rotated to bring its 115 pointer 45 into register with the same "release" mark r to withdraw the several locking pawls.

In order to return the annulus 13 to its original or zero position as exhibited 120 through an aperture 46 in the face plate of the instrument, I provide on the other end of the wrench 44 a pin-projection 47 which may be passed from the under side of the base plate 10 through a concentric slot 48 125 into any one of a series of apertures 49 provided on the under side of the annulus 13. Inasmuch as the slot 48 extends for an angular distance of about ninety degrees, and 130 inasmuch, furthermore, there are five aper-

tures 49 provided in the annulus one of such apertures will always be within the reach of the wrench pin 47, through the slot 48.

The present device is adapted to be attached to the coat of the player by a strap or pin which may be secured to the loop L of the instrument, and the several readings of the perspective index wheels w can readily be seen through apertures 50 provided for 10 that purpose in the cover plate 20.

The operation of the device is as follows:—

The parts of the instrument being in the position shown and giving registration as 15 exhibited in Fig. 1, the knob 34 is turned to bring its pointer 33 into register with the release mark r. The cam 41 is then turned by the wrench 44 to bring its pointer 45 also into register with said mark, which action 20 will allow the several return springs 40 to perform their functions and reset all of the several index wheels w back to zero. The pin 47 of the wrench may then be inserted through the slot 48 into one of the apertures 25 49 of the annulus and the latter may then be turned until its figure "0" appears in proper position under the aperture 46 in the face plate. The finger knob 34 is then turned until its pointer 33 registers with the 30 number plate 1, to indicate that the player is going toward the first hole. This position of the pointer and the cam 31 is now such that the pinion pertaining to the register-wheel which belongs to hole number 1, will 35 be in mesh with the annulus, and after every stroke or "putt" which the player then makes, the finger lever 18 is operated once, therefore advancing the annulus one notch and also turning the register wheel pertaining to hole 40 number "1" for the distance of one space, this action being repeated until the player has made hole number 1, and he then turns the knob 34 to bring its pointer 33 into register with number plate "2" indicating that he 45 is now progressing toward the second hole of the course. This change in position will rotate the cam 31, drawing the first slide inwardly to bring its pinion into locked position with its retaining dog 37, when the 50 second slide is pushed outward to bring the teeth of its pinion into engagement with the teeth of the annulus, whereupon each stroke is registered as before. The same position and change takes place after the player has 55 made the several holes in succession. As shown, the instrument gives evidence that the player has used six "putts" to make the first hole; that he has used five strokes to make the second hole, and that, up to the 60 point of registration, he has used seven strokes toward making the third hole. The instrument also shows that the total number of strokes thus far employed from the beginning of the game is eighteen, which number 65 of course corresponds to the sum of the

individual recordings pertaining to the several holes mentioned.

Changes may be made in the general organization, as well as in the particular construction of some of the elements of my improved device, without departing from the spirit of the invention, especially in the manner of operating the several slides above referred to, and in the manner of releasing the index wheels or their controlling means 70 from their locking devices above described. Likewise it should be understood that it is immaterial what number of holes the present device is adapted for, and that, if desired, the same mechanism pertaining to the 75 first nine holes can be duplicated on the reverse side of the base plate so as to adapt the instrument for registering the game in which eighteen holes constitutes the regulation number.

85

I claim:—

1. In a device of the character described, a series of individually operable register wheels, a total register, means common to all register wheels and adapted to set each register wheel successively into operative relation with the total register, and means for operating the total register to advance the set register wheel one indication at a time.

2. In a device of the character described, 95 a series of individually operable register wheels, a gear for each register wheel, a slide on which each gear and register wheel set is mounted, the slides being movable radially from a center, a total register provided with internal gear teeth surrounding the series of gears of the register wheel sets, a cam having a cam groove formed therein, a pin on each slide engaging in the groove, the groove having a single "high point" 100 whereby on rotation of the cam the slides are moved consecutively into and out of engagement with the internal gear, and means for advancing the total register one indication at a time, the movement being indicated 105 both by the total register and the engaged register wheel.

3. In a device of the character described, a series of individually operable register wheels arranged in a circle, a gear wheel for 115 operating each register wheel, a total register surrounding said series of register wheels having internal gear teeth formed thereon for engagement by the register wheel gears, means common to all register wheels for 120 moving any single register wheel gear into engagement with the total register gear, and means for advancing the total register to move the set register wheel one indication at a time, the total register displaying the 125 number of times operated.

4. In a device of the character described, a series of individually rotatable register wheels, a rotatable total register, a slide on which the register wheels are mounted, a 130

- gear for each register wheel, the total register being provided with internal gear teeth with which the gear of each register wheel is adapted to engage, means for moving the slides consecutively to bring the gear wheels of the register sets into engagement with the internal gear of the total register whereby advancement of the total register rotates the set register wheel.
- 10 5. In a device of the character described, a series of individually operable register wheels, a gear wheel for operating each register wheel, a slide providing a mounting for each gear and register wheel set, a total register having internal gear teeth, means common to the slides adapted to move the same in consecutive order to bring the gear thereon into engagement with the internal gear, and means for moving the total register in a manner to advance the register wheel of the engaged gear one indication at a time, the total register giving an indication of the number of times operated.
6. In a device of the character described, 25 a casing, a series of independently operable register wheels arranged in a circle therein, each bearing numbers arranged in consecutive order from zero, the casing having an aperture for each register wheel through which a number may be displayed, a total register surrounding the register wheels, and means common to all the register wheels for moving the same in succession into and out of operative relation with the total register.
7. A game counter for use in playing the game of golf comprising a casing, a series of register wheels rotatably mounted therewithin wholly independently one of the other and adapted to register the number of strokes employed in making any one "hole", a casing having an aperture for each register wheel through which a number thereon may be displayed, each aperture being numbered or characterized to correspond with the number of the "hole" with which it is to be used, a total register wheel surrounding the said series of register wheels being rotatable in the casing and bearing numbers in consecutive order beginning with zero, the casing having an aperture through which a number on the total register may be displayed, means common to the register wheels whereby they may be brought successively into operative relation with the total register, and means for actuating the total register from the exterior of the case in a manner to advance the engaged register wheel one indication at a time, the total register displaying the number of times operated and thus giving a total of the numbers displayed by the several register wheels.

In testimony whereof I affix my signature in presence of two witnesses.

DAVID L. MURCHEY.
